United States Patent Office.

CHARLES E. HENDRICK, OF CHICOPEE, MASSACHUSETTS.

Letters Patent No. 81,369, dated August 25, 1868.

IMPROVEMENT IN FEATHER-RENOVATORS.

The Schedule referred to in these Letters Patent and making part of the same.

TO ALL WHOM IT MAY CONCERN:

Be it known that I, CHARLES E. HENDRICK, of Chicopee, in the county of Hampden, and State of Massachusetts, have invented a new and useful Improvement on a Machine for Renovating Feathers; and I do hereby declare that the following is a full, clear, and exact description of the construction and operation of the same, reference being had to the annexed drawings, making a part of this specification, in which—

Figure 1 is a vertical section taken on the line *y z*, fig. 2.

Figure 2, a transverse section taken on the line *w x*, fig. 1.

Figure 3 is the valve-key, containing a square socket, fitting all the valves.

This improvement comprises a new valve and steam-conveyer arrangement for feather-renovating machine.

Similar letters of reference indicate corresponding parts.

The machine consists of supports, A, to flanged trunnions C and D, turning on bearings G, united by bolts with feather-box B, of octagon shape, having drier E running through centre, with steam-conveyer F inside, having branches, *i*, passing through sides of drier E, opening into the feathers, steam being introduced through inlet-pipe K to valve-chamber P, passing through conveyer F and branches into feathers, by opening the valves O O, and shutting the disk-valves *m* and *n*, covering the openings, L, into drier, operating in annular valve-chambers P P, in trunnions G G, by turning key, fig. 3, when applied to the part of the valve outside seen in fig. 1; shutting off the steam from the feathers by closing valves O O, and opening the valves *m* and *n* to drier E, steam passing into valve-chamber P, to outlet *t*, in trunnion D, through annular groove *r* around trunnion, communicating with waste-pipe *j*, water passing off through water-pipe *u*, handle H turning machine. Door Q, to admit feathers, closed by latch *g*.

Fig. 1 represents it with four valves, though only three, O O *n*, are absolutely necessary.

The operation is as follows: By closing the valves *n* and *m* when used, (if desired,) by applying the key, closing up drier E, and opening valves O O, to conveyer F, allowing the steam to pass into feathers, steaming them; by closing up the valves O O to conveyer, and opening the valves *n* and *m*, if used on machine, the steam passes into drier E, sending out heat into the feathers, drying them, and passing off.

I claim the annular chambers P P, in combination with the valves O O *m n*, and conveyer F, provided with branches *i*, drier E, and feather-box B, when constructed, arranged, and operated substantially in the manner shown and described, for the purpose set forth.

CHARLES E. HENDRICK.

Witnesses:

E. HENDRICK,

AMORY DOOLITTLE.
